UNITED STATES PATENT OFFICE.

JOSEPH H. SAVILL, OF CAMDEN, NEW JERSEY.

ADJUSTABLE DRAINBOARD.

1,198,775.

Specification of Letters Patent. Patented Sept. 19, 1916.

Application filed May 15, 1916. Serial No. 97,496.

To all whom it may concern:

Be it known that I, JOSEPH H. SAVILL, a citizen of the United States, residing at Camden, in the county of Camden and State of New Jersey, have invented new and useful Improvements in Adjustable Drainboards, of which the following is a specification.

My invention relates to new and useful improvements in adjustable drain boards, and has for its object to provide an exceedingly simple and effective device of this character which may be readily and quickly attached to the wall of a building or other object adjacent a sink, whereby dishes or other objects placed upon the drain board proper will be drained, and the water permitted to flow therefrom into the sink.

A further object of the invention is to provide an adjustable drain board whereby the board proper may be raised to a vertical position, and folded against the wall of the building, so that it will be out of the way while cleaning.

With these ends in view, my invention consists in the details of construction and combination of elements hereinafter set forth and then specifically designated by the claims.

In order that those skilled in the art to which this invention appertains may understand how to make and use the same, I will describe its construction in detail, referring by numerals to the accompanying drawing forming a part of this application, in which—

Figure 1, is a front elevation of my improved adjustable drain board showing its position with relation to the sink while in use. Fig. 2, is a similar view with the drain board raised, also showing in dotted lines the first raised position of the board before folding it against the object supporting it, such as the wall of the building. Fig. 3, is a plan view of the support with the drain board proper removed. Fig. 4, is a side elevation thereof; and Fig. 5, is a section at the line 5—5 of Fig. 3.

In carrying out my invention as here embodied 2 represents the drain board proper which may be of any desirable material, and of any approved shape or style which is attached to the bridge 3 in any suitable manner as by screws passing through holes 4 in said bridge and into the drain board proper. The bridge is provided with a pair of in-

tegral spaced lugs 5 each of which is provided with an extension or toe 6, and these lugs are pivoted to the lugs 7 as by a rod 8, said lugs 7 being formed integral with the 60 supporting arm 9, the lower edges of said lugs 7 lying below the upper edge of the supporting arm 9 as plainly shown in Fig. 4. The inner end of the supporting arm is enlarged and provided with the integral 65 lugs or hinge members 10 whereby said supporting arm is pivoted or hinged to the bracket arms 11 in some suitable manner as by the rod 12, and said bracket arms are formed integral with the bracket plate 13 70 which is secured by screws 14 or their equivalent to some supporting object, which pass through holes formed in the bracket plate. The support is fastened adjacent the sink 15 so that when the drain board 2 is in its 75 lower or approximately horizontal position, the outer or free end thereof will rest upon the edge of said sink, so that the water draining from the objects upon the drain board will run into said sink.

When it is desired to clean the sink or in the locality thereof, said drain board may be raised and folded out of the way by first swinging the same upward about the pivot 8 until the extensions or toes 6 engage the 85 under edge of the supporting arm 9 which act as stops to limit the upward movement of the drain board proper, this position being shown in dotted lines in Fig. 2. After the drain board is raised to the position just 90 indicated it may be further swung out of the way against the object to which the support is attached by swinging the supporting arm 9 about its pivot 12, this last position being shown in elevation in Fig. 2. By reversing the movements just described, the drain board may be readily returned to its horizontal or working position, and when in this last named position, the inner edge of the bridge 3 engages one of the faces of the 100 supporting arm 9 so as to support the drain board 2 in its proper position.

Of course I do not wish to be limited to the exact details of construction as herein shown, as these may be varied within the 105 limits of the appended claims without departing from the spirit of my invention.

Having thus fully described my invention, what I claim as new and useful, is—

1. An adjustable drain board comprising 110 a bracket, a supporting arm pivoted thereto to swing substantially horizontally, a bridge

- pivoted to said supporting arm at one side thereof, so that the board supporting face can swing to a horizontal or vertical position and a board secured to said bridge.
5. 2. An adjustable drain board comprising a bracket, a supporting arm pivoted thereto to swing substantially horizontally, a bridge pivoted to said supporting arm at one side thereof, so that the board supporting face 10 can swing to a horizontal or vertical position, said bridge being provided with means for engaging the lower edge of the supporting arm to limit the movement of said bridge in one direction, and a board secured to said 15 bridge.
3. An adjustable drain board comprising a bracket, a supporting arm pivoted thereto to swing substantially horizontally, a bridge, integral lugs formed therewith, means for 20 pivoting the same to the supporting arm, toes or extensions formed integral with said lugs arranged to engage the lower edge of the supporting arm for limiting the movement of said bridge in one direction, and a 25 board secured to said bridge.
4. An adjustable drain board comprising a bracket, a supporting arm pivoted thereto to swing substantially horizontally, lugs formed integral therewith and projecting 30 from one face thereof, the upper edge of said lugs lying below the upper edge of the supporting arm, a bridge, lugs formed integral with said bridge and projecting from one face thereof, means for pivoting the 35 bridge to the supporting arm through the medium of said lugs, a toe formed with each of the lugs carried by the bridge and arranged to engage the lower edge of the supporting arm to limit the movement of said 40 bridge in one direction and act as a stop, and a board secured to said bridge.
5. An adjustable drain board comprising a bracket, a supporting arm enlarged at one end, horizontal lugs or hinge members 45 formed with said enlarged end and projecting therefrom, a rod passing through said lugs for pivoting the supporting arm to
- the bracket, a pair of vertical lugs formed integral with the supporting arm and projecting from one face thereof, the upper edge of said lugs lying below the upper edge 50 of the supporting arm, a bridge, lugs formed integral with said bridge and projecting from one face thereof, means for pivoting the bridge to the supporting arm through the medium of said lugs, a toe formed with each of the lugs carried by the bridge and arranged to engage the lower edge of the supporting arm to limit the movement of said bridge in one direction and act as a 55 stop, and a board secured to said bridge.
6. An adjustable drain board comprising a bracket consisting of a bracket plate and superposed bracket arms projecting therefrom, a supporting arm enlarged at one end, 60 lugs formed integral with said supporting arm at the enlarged end thereof, a rod passing through said lugs and the bracket arms for pivoting the supporting arm thereto, lugs formed integral with said supporting 65 arm and projecting from one face thereof, the upper edges of said lugs lying below the upper edge of the supporting arm, a bridge, lugs formed integral therewith and projecting from one face thereof, toes formed with 70 said lugs, a rod passing through the bridge lugs, and the lugs projecting from the face of the supporting arm for pivoting said bridge to said supporting arm, one edge of said bridge arranged to engage one face of 75 the supporting arm to limit the movement of said bridge in one direction, said toes arranged to engage the lower edge of the supporting arm to limit the movement of said bridge in the opposite direction, and a board 80 carried by said bridge.
- In testimony whereof, I have hereunto affixed my signature in the presence of two subscribing witnesses.

JOSEPH H. SAVILL.
